US0D1025487S

(12) United States Design Patent (10) Patent No.: US D1,025,487 S
(45) Date of Patent: * Apr. 30, 2024

(54) SHAYER

(71) Applicant: Shenzhen Patpet Technology Co., Ltd., Shenzhen (CN)

(72) Inventor: LinXian Li, Beijing (CN)

(73) Assignee: Shenzhen Patpet Technology Co., Ltd.

() Term: 15 Years

(21) Appl. No.: 29/790,084

(22) Filed: Nov. 3, 2021

(51) LOC (14) Cl. 28-03

(52) U.S. Cl.

USPC D28/50
